Inventor

By Geo. Kimmel Attn: Mrs. [unclear]

UNITED STATES PATENT OFFICE.

ARLO B. HARRIS, OF ELDORA, IOWA.

GATE.

1,264,788.

Specification of Letters Patent. Patented Apr. 30, 1918.

Application filed June 6, 1917. Serial No. 173,127.

To all whom it may concern:

Be it known that I, ARLO B. HARRIS, a citizen of the United States, and resident of Eldora, in the county of Hardin and State 5 of Iowa, have invented certain new and useful Improvements in Gates, of which the following is a specification.

This invention relates to new and useful improvements in gates, and more particularly to farm gates, and the primary object of the invention is to provide a swinging gate with means whereby the same may be lifted a short distance so as to clear snow, or for various other purposes which are 15 obvious.

Another object of the invention is to provide a device of this character, which is easily and simply constructed, inexpensive to manufacture, and one which will be very 20 efficient in operation.

With these and numerous other objects in view, my invention consists of the novel features of construction, combination and arrangement of parts which will be herein referred to and more particularly pointed out in the specification and claims.

In the accompanying drawings:

Figure 1 is a side elevation of the gate; and 30 Fig. 2 is a detail perspective view of the lifting means detached.

In describing my invention I shall refer to the drawings in which similar reference characters will designate corresponding parts 35 throughout the several views. The invention is adapted to be applied to the conventional type of gate 1 that is of substantially rectangular shape, being formed with horizontally extending rails, having their opposite 40 ends, at intermediate portions connected by brace bars 2, as is common to farm gates of this character. The gate is normally positioned between a hinge post 3, and a latch post 4, the rear end of said gate being connected 45 to the hinge post by slideable and swinging connections to be hereinafter more fully described.

This connection comprises a pair of U-shaped supports 4', which have their end 50 portions positioned through said post, and their connected ends being spaced from one side of the post. These connected ends are disposed in substantially vertical alinement, and the same are adapted to receive between 55 their inner sides and the post rollers 5 that are mounted on strap members 6 secured to

the end bars 2 of the gate 1. This allows the gate to be hingedly and slidably mounted between the posts. The forward end of the gate 1 is provided with the conventional type 60 of sliding latches 7, that are adapted to project forwardly into keepers 8 in the latch post 4 when the gate is in closed position.

Pivotedly connected to one of the horizontally extending rails of the gate 1, is a bell 65 crank lever 9 having one of its arms projecting laterally from the end bar of the gate, and hinged intermediate its ends as shown at 10, said projecting portion having a lateral off-set 11 at the free end thereof 70 that is adapted to be pivotally mounted in a socket formed in the gate post 3. The other arm of the lever 9 has a knuckle 12 formed thereon that projects from opposite sides of the gate for a purpose to be hereinafter 75 more fully described. An operating lever 13 is pivotally mounted adjacent the front end of the gate 1. Said lever 13 is formed of two vertically positioned bars 14 and 15, that are positioned on opposite sides of the gate, 80 and are pivotally connected with one of the rails 2 adjacent their lower ends as shown at 16. The bars 14 and 15 are connected at their upper ends, one of said bars projecting upwardly as shown at 17 and being bent 85 laterally to form a handle, whereby the said bars may be operated simultaneously.

A pair of parallel links 18 disposed on opposite sides of the gate 1 connect the free end of the bell crank lever 9, with the bars 90 14 and 15. These links extend along the gate 1, and where they are connected with the lower ends of the bars 14 and 15 is also connected a diagonally extending guide and brace bar 19 that extends across the gate 1, 95 and above the same as shown at 20, the free end thereof being held in said position by upright standards 21 secured on the gate at the rear end thereof. To prevent sagging the gate 1 is provided with a supplemental diagonally extending rod 22 which forms a brace for the same. To operate the latches 7 simultaneously with the operation of the lever 13, there is provided a supplemental pivoted lever 23 that is mounted on 100 one side of the gate 1 adjacent the forward end thereof, and is connected by a link at 24 that extends upwardly and is pivotally attached to the bar 14. The lower end of the lever 23 is connected with the rear end 110 of the lower sliding latch 7. The upper sliding latch 7 is connected with the bar 15,

above the link 24, and by this connection it is obvious that when the operating lever 13 is swung rearwardly, the upper and lower sliding latches will be retracted from the 5 keepers 8, so as to allow the gate to lift as the same is disconnected from the latch post 4.

From the foregoing description the operation of this gate is easily understood. 10 Owing to the connection of the said gate with the gate post 3, the gate may be swung in the conventional manner, and when it is desired to raise said gate, the operating lever 13 is grasped by the projecting upper end 15 thereof which may if desired be connected with a cable which is run to any suitable place so as to facilitate the operation thereof, and the bars are moved rearwardly, thereupon the links 18 will move forwardly and 20 as the said links are connected with the bell crank lever 9, and as the opposite end of the said lever is engaged with the stationary post 3, it is obvious that the gate 1 will be lifted thereby. The slideable hinge connection 25 between the gate post permits a limited lifting movement of the gate. The brace bar 19 with the projecting portion 20 operates as a primary brace which with the diagonal brace bar 22 prevents the gate from sagging 30 during operation thereof.

It is obvious that movement of the lever 13 will release the latches 7 from the latch post 4, and permit this sliding movement of the gate. This limited vertical sliding movement of swinging gates is very useful in 35 farm gates, which allows the gate to be swung when lifted to operate when there is a heavy snow fall on the ground. The gate is also adapted to be lifted slightly to allow 40 small animals to pass therethrough, but still retain the larger animals and prevent their escaping.

From the above description taken in connection with the accompanying drawings, 45 it is thought that a clear and comprehensive understanding of the construction, operation, and advantages of my invention may be had, and while I have shown the device

as embodying a specific structure, I desire to have it understood that such changes may 50 be made in said structure as do not depart from the spirit and scope of the invention as claimed.

Having fully described my invention, what I claim as new, and desire to secure by Letters Patent is:

1. A swinging gate of the class described including a gate hingedly and slidably connected with a gate post, a bell crank lever pivoted on the gate adjacent the post and 60 pivotally connected therewith, a pair of vertically positioned bars pivoted on opposite sides of the gate adjacent the front end, said bars having their upper ends connected and forming a handle projecting above the 65 gate, parallel links on opposite sides of the gate connecting said bars with the bell crank lever, and diagonal extending rods carried by the gate and having their lower ends connected with the joints of the operating 70 bars and links.

2. A swinging gate of the class described including a gate hingedly and slidably connected with a gate post, a bell crank lever pivoted on the gate adjacent the hinged end 75 thereof, one arm of said lever projecting from the end of the gate, and the other extending downwardly substantially parallel therewith, the projecting arm of said lever being pivotally connected with the gate post 80 so as to allow the gate to swing in a vertical and horizontal plane, a vertically disposed operating lever hingedly mounted on the gate adjacent the forward end thereof, a link connecting the lower end of said operating lever with the extremity of the downwardly projecting arm of the bell crank lever, latches carried by the gate and adapted for engagement with a latch post, and means connecting the operating lever and 85 the latches for retracting said latches upon 90 operation of the lever.

In testimony whereof, I affix my signature hereto.

ARLO B. HARRIS.
